US00D372262S

United States Patent [19]
Carter

[11] Patent Number: Des. 372,262
[45] Date of Patent: *Jul. 30, 1996

[54] TYPE FONT

[76] Inventor: Matthew Carter, 36A Rice St.,
Cambridge, Mass. 02140
[] Term: 14 Years
[21] Appl. No.: 15,158
[22] Filed: Nov. 9, 1993
[52] U.S. Cl. D18/24
[58] Field of Search D18/24-33

[56] References Cited
